UNITED STATES PATENT OFFICE.

STEPHEN M. SMITH, OF BOISE, IDAHO.

SALVAGING APPARATUS.

1,246,172.

Specification of Letters Patent. Patented Nov. 13, 1917.

Application filed September 5, 1916. Serial No. 118,572.

To all whom it may concern:

Be it known that I, STEPHEN M. SMITH, a citizen of the United States, residing at Boise, in the county of Ada and State of Idaho, have invented certain new and useful Improvements in Salvaging Apparatus, of which the following is a specification.

This invention relates to salvaging apparatus and more particularly to apparatus 10 designed for raising sunken boats; although it is applicable to many other uses, such as dredging and other submarine work, and is not limited to the particular application hereinafter described. This apparatus is 15 also designed for use as a floating high sea dock, and is adapted to lift a ship at sea and repair the same and to enable it to resume its voyage under its own power.

One of the objects of the present invention is to provide a practical apparatus particularly adapted for raising sunken boats and the like which will be reliable and efficient in use and operation. A further object is to provide an apparatus of the above 25 character which may be easily controlled and moved to desired localities and which will be exceedingly stable while in use.

Other objects will be in part obvious from the annexed drawings and in part indicated 30 in connection therewith by the following analysis of this invention.

This invention accordingly consists in the features of construction, combination of parts and in the unique relations of the 35 members and in the relative proportioning and disposition thereof, all as more completely outlined herein.

To enable others skilled in the art so fully 40 to comprehend the underlying features thereof that they may embody the same by the numerous modifications in structure and relation contemplated by this invention, drawings depicting a preferred form have been annexed as a part of this disclosure, 45 and in such drawings like characters of reference denote corresponding parts throughout all the views, of which

Figure 1 is a front elevational view of the complete apparatus; 50 Fig. 2 is a side elevation of part of the same;

Fig. 3 is a sectional view of a portion of one of the parts; and

Fig. 4 is a horizontal sectional view 55 through the upper part of a modified form of construction, such as shown in Fig. 3.

Referring now to the drawings in detail and more particularly to Fig. 1, 5 and 6 denote a pair of steamships. Both of these ships are complete in themselves, being 60 equipped with the necessary motive power, steering gearing, engines, and machine repair shops, as well as auxiliary engines and auxiliary motive power for controlling the hoisting apparatus hereinafter described 65 and positioning the apparatus as a whole with respect to the sunken boat to be raised.

These ships are rigidly connected together by a series of elongated arches 7, made of structural steel or the like, and extending 70 throughout a major portion of the length of the ships. The upper part of the arches is provided with a track way 8 along which traveling cranes 10 are adapted to travel. From each crane is supported a grapple or 75 other suitable form of attaching means 11, by means of cables 12, so arranged as to be lowered over a sunken boat 13 secured thereto in a manner such as shown in Fig. 1. Power is then applied to the hoisting cables 80 to raise the boat.

Both ships 5 and 6 are also connected by bridges 14 fore and aft to increase the 85 steadiness of the entire apparatus and also to permit ready passage from one ship to the other. After the sunken boat has been raised, clear of the water if so desired, and is suspended as by means of cables passing thereunder from the ship 5 to the ship 6, the necessary repairs may be made thereon, 90 whereupon the repaired boat may be returned to the water and continue its voyage under its own power.

It is to be noted that both ships 5 and 6 are provided with laterally extending propellers 15 both fore and aft which may be raised and lowered as required and connected with the main source of power in order to permit a positioning of the apparatus or a complete turning thereof within its 100 own length. Normally these propellers are raised out of the water.

Both ships 5 and 6 are also provided with derricks 16 having movable booms 18 from which is suspended an observation and 105 grappling device 20, as shown clearly in Fig. 3. The grappling part of this device is fully illustrated and described in my Patent No. 1,145,220, and needs no detailed description of its construction and operation 110 at this time. The upper part, however, is provided with a steel chamber 21 of sub-

stantial thickness in order to properly withstand the strains to which the device may be put at great depths. This chamber is provided with a suitable manhole or inlet 22 5 countersunk in one side thereof and numerous dead lights or port holes 23 similarly constructed are provided at various points to permit observation in all directions.

The interior of this chamber is provided 10 with a suitable reservoir tank 24 in which compressed air may be stored for use of the observers. An electrically operated pump 25 is provided for expelling the used air as fresh air is admitted from the supply tank 15 through suitable automatic air valves 26. It is of course to be understood that the interior of the chamber which is of sufficient size to accommodate one or more observers is also properly equipped with electric 20 lights, both inside and out, telephones, etc., thereby to permit a ready observation in all directions, and telephone instructions to the power operator as to the relative position of the apparatus with respect to the boat or 25 object to be raised, as well as other essential details required for preserving proper atmospheric conditions and the proper controlling of the apparatus.

In Fig. 4 is shown a modified form of observation chamber having a plurality of air chambers 24 about the side walls with passageways leading to the side walls and openings 23 in the floor to permit observation straight down.

35 It is also frequently necessary to remove drifted sand and rocks from about the hull or boat to be raised in order to permit the grappling arms 11 or other attaching means to be properly positioned or secured thereto, 40 and my apparatus is especially adapted for this work.

It is believed that the method of use and operation of an apparatus of this character will be clear from the above disclosure to 45 those familiar with the subject and a further discussion thereof is unnecessary.

It will be seen that the apparatus is of simple and practical construction, reliable, stable and efficient in use and operation and 50 adapted to accomplish, among others, all of the objects and advantages herein set forth.

Various modifications in structure and material may be made in the apparatus without departing from the spirit of the invention. For instance the entire observa- 55

tion chamber may be made of heavy glass if desired and instead of having air reservoirs therein the man may wear individual helmets supplied from above similar to the helmets worn in mine rescue work.

60

Without further analysis, the foregoing will so fully reveal the gist of this invention that others can by applying current knowledge readily adapt it for various applications without omitting certain features 65 that, from the standpoint of the prior art, fairly constitute essential characteristics of the generic or specific aspects of this invention, and therefore such adaptations should and are intended to be comprehended within the meaning and range of equivalency of 70 the following claims.

70

I claim:

1. In an apparatus of the character described, in combination, a pair of ships 75 spaced apart, each of said ships being complete in itself, an archway connecting said ships longitudinally, a longitudinal track way for a hoisting device extending beneath and longitudinally of the archway, and 80 movable hoisting devices suspended from said track way.

2. In an apparatus of the character described, in combination, a pair of ships 85 spaced apart, each of said ships being complete in itself, bridges connecting said ships to permit passage from one ship to the other, an archway connecting said ships longitudinally, a longitudinal track-way for a hoisting device extending beneath and longitudinally of the archway, and movable hoisting devices suspended from said track-way.

3. In an apparatus of the character described, in combination, a pair of ships 95 spaced apart, each of said ships being complete in itself, laterally movable derricks carried by each of said ships, an archway connecting said ships longitudinally, a longitudinal track-way for a hoisting device 100 extending beneath and longitudinally of the archway, and movable hoisting devices suspended from said track-way.

In testimony whereof I affix my signature in presence of two witnesses.

STEPHEN M. SMITH.
